CLAIM

The ornamental design for keyboard, as shown and described.

DESCRIPTION

FIG. 1 is a top plan view of a keyboard showing my new design;

FIG. 2 is a front elevational view thereof;

FIG. 3 is right side elevational view thereof;

FIG. 4 is a bottom plan view thereof;

FIG. 5 is a rear elevational view thereof; and

FIG. 6 is a top, front, right side perspective view thereof, on an enlarged scale.

The left side elevational view of the keyboard is identical to the right side elevational view thereof.

FIG. 1

FIG. 2
